DESIGN FOR A COMBINED BOOK MARKER AND LINE GUIDE

Emeline Mears, Pasadena, Calif.

Application September 15, 1941, Serial No. 103,361

Term of patent 14 years

To all whom it may concern:

Be it known that I, Emeline Mears, a citizen of the United States, residing at Pasadena, in the county of Los Angeles and State of California, have invented a new, original, and ornamental Design for a Combined Book Marker and Line Guide, of which the following is a specification, reference being had to the accompanying drawing, forming a part thereof.

In the accompanying drawing, Fig. 1 is a top plan view of a combined book marker and line guide showing my new design.

Fig. 2 is a bottom plan view thereof; and
Fig. 3 is a side elevation thereof.

I claim:

The ornamental design for a combined book marker and line guide, as shown.

EMELINE MEARS.
